CLAIM

I claim the ornamental design for a display screen with graphical user interface for a modular device, as shown and described.

DESCRIPTION

FIG. 1 is a front view of a first embodiment of a display screen with graphical user interface for a modular device, showing my new design; and,

FIG. 2 is a front view of a second embodiment thereof. The outermost broken-line shows the perimeter of a display screen or portion thereof and forms no part of the claimed design. The remaining broken lines illustrate portions of a graphical user interface and form no part of the claimed design.
